FLUID INLET PIPE FOR RADIAL FLOW ELASTIC FLUID TURBINES

Oscar Anton Wiberg, Finspong, Sweden

Application June 26, 1944, Serial No. 542,203
In Sweden July 3, 1943

1 Claim. (Cl. 253—16.5)

This invention relates to radial flow elastic fluid turbines of the type having an added set of axial flow blades and in which the driving fluid is admitted through pipes leading to chambers provided in fluid chests located on both sides of the turbine inside the turbine casing.

Hitherto, as a rule, said pipes have been connected to the fluid chests from below, which has resulted in an unequal heating of the stationary inner members of the turbine and an unsuitable location of the pipes from a streaming point of view.

The invention has for its object to provide an improved arrangement of the pipes in order to allow the placing thereof at the greatest distance possible from the axial blade system of the turbine. This leads to the advantage that the pipes may not interfere with the flow of driving fluid, hereinafter referred to as steam, as exhausted from the axial flow system or only interfere with same to a neglectable extent, thereby avoiding detrimental vibrations of the radially positioned blades of the axial flow system.

According to the invention the ends of the steam inlet pipes connected to the steam chests are located in or adjacent to the horizontal plane that may be laid through the joint between the upper and lower halves of the turbine casing.

In the accompanying drawing an embodiment of the invention is illustrated. Fig. 1 is a horizontal central section of part of a radial flow turbine having an added set of axial flow blades. Fig. 2 is a diagrammatic illustration, showing on a smaller scale than that of Fig. 1 a vertical cross section on the line II—II of Fig. 1, of some of the elements shown in Fig. 1, as the turbine casing with steam chest, inlet pipe and stays therein.

The turbine shown in the drawing is of the double rotation type. In Fig. 1 the end of one of the oppositely rotatable turbine shafts is shown and designated by the reference numeral 1. The respective turbine shaft is indicated at 3. It is mounted in conventional way in the turbine casing 2. Shaft end 1 supports the turbine disc 4 which is sealed to the shaft end by the screw 5. The blading supported by the disc 4 comprises a set of radial flow blades 6 and added set of axial flow blades 7.

Inserted between the turbine disc 4 and the turbine casing 2 is a steam chest 8 surrounding the shaft end. Said steam chest contains two concentric steam chambers 9 and 10, bounded axially at their side facing the blading 6 by means of a disc 11 belonging to a labyrinth packing. Said packing includes in addition to the

disc 11 another disc attached to the turbine disc 4 and sets of tightening strips in the usual way.

The steam chest is supported by a supporting ring 12 bolted to the turbine casing 2 inside flange 13. Where the shaft end passes through the steam chest it is surrounded by a labyrinth type of shaft packing 14.

The steam is admitted to the turbine through pipes 15 connected to the steam chest. According to the present invention said pipes are so positioned as to approach the steam chest along or approximately along the horizontal plane that may be laid through the joint 16 of the turbine halves.

15 As will appear from Fig. 1, said positioning of the steam inlet pipes permits directing the portions of the pipes lying in or adjacent to said horizontal plane in an oblique outward direction as reckoned from the central part of the turbine without any trouble as far as the mounting of the pipes is concerned. By this means the pipes may be located at a greater distance from the axial flow system, thereby reducing their disturbing effect on the flow of steam as exhausted from the axial flow system and the imparting of vibrations to said system as well. Another advantage involves the symmetric admission of steam to the steam chest with a resulting uniform heating of the steam chest, the supporting ring 12 and the turbine casing, thereby avoiding displacements of steam chests and labyrinth packings. By this means the wear of the tightening strips of said packings may be reduced.

35 The pipes 15 comprise, preferably, a straight portion 15' secured to the steam chest by a rolling operation, a curved portion 15'' welded at 19 to the portion 15' which is only as long as necessary for allowing its mounting and dismantling without interfering with the stays 17 in the turbine 40 casing, and an outer portion 15''' welded at 19' to the portion 15'' or connected thereto by mechanical connecting elements, as indicated at 18. The welded joints between the pipe sections 15', 15'' and 15''' are designated by the reference 45 numeral 19 in the drawing.

What I claim is:

In an elastic fluid turbine, in combination, a central blade system for radial flow of elastic driving fluid, a blade system for axial flow of elastic fluid, located at a greater radial distance from the axis of the turbine than the outermost blade ring of the radial system and axially displaced with relation to the radial system for receiving the driving fluid discharged therefrom, 50 a turbine casing for enclosing said blade systems,

said casing comprising two members joined along a horizontal plane extending approximately through the turbine axis, said casing further comprising a driving fluid chest having at least two concentric chambers for admitting driving fluid to radially spaced points of the radial flow blade system, pipes connected to said chambers for supplying driving fluid thereto, said pipes being located with a portion of their length in front of the outlet end of the axial flow blade system, and connections between said pipes and said chambers located near the level of said horizontal joint between the members of the casing, the portion of the pipes next to the chambers being located in proximity to the horizontal plane through said joint symmetrically with respect to said horizontal plane as well as with respect to the vertical plane through the axis of the turbine, the portions of the pipes in front of the axial blade system being located at a greater distance

from the centre of the turbine as represented by the radial flow system than the ends of the pipes connected to the fluid admission chambers.

OSCAR ANTON WIBERG.
